MANUFACTURING SUBSTITUTED HYDROXY- ω -AMINO-ACETOPHENONESHelmut Legerlotz, Berlin, Germany, assignor to
Frederick Stearns & Company, Detroit, Mich.No Drawing. Application May 2, 1928. Serial
No. 274,667, and in Germany August 16, 1926

3 Claims. (Cl. 260—128.5)

This invention has reference to hydroxylated acetophenones and in particular to N-alkyl-substituted, as well as to N-aryl-substituted so-called hydroxy- ω -amino-acetophenones, and it is one of the objects of this invention to devise a method of manufacturing such products by means of which extremely high yields of such products may be obtained in a comparatively easy and not complicated manner. It is well known that according to the previous art (see for instance Archiv für Pharmacie 237, page 222) the reaction of halogen-compounds of the type

where X designates a halogen, with amines for the formation of bodies of the general type

where R means an alkyl or an aryl-radical results in very unsatisfactory low yields, and in most cases moreover, this reaction produces mixtures which can only be separated with great difficulty. In view of these facts some scientists, Gabriel for instance, following the indications of the Hinsberg-method have suggested to substitute in the compounds above mentioned the halogen by the methyl-amino-residue and by the aid of the potassium-salt of the para-toluol-sulfon-methylamine (Berichte d. Chemisch. Gesellsch 47, page 1336)

However the investigations of Gabriel did not extend to the treatment of bodies of the general type

that is to say to the derivatives of the above mentioned compounds having a mono-hydroxylated nucleus. Now, in view thereof, it constitutes an important and unexpected progress in this particular art that of these hydroxylated compounds it is possible to obtain bodies of the general composition

by a similar treatment, that is to say, by acting thereupon with one molecule para-toluol-sulfon-methyl-amino-potassium-salt in a solution of acetone, though but a low yield of these bodies is obtained. The yield is not improved by the substitution of the hydroxyl-group by some sorts

of radicals, while, on the other hand the substitution of only the hydrogen of the hydroxyl-group by other kinds of radicals (alkyls or acyls) produces very satisfactory and sometimes almost theoretical yields. Gabriel states expressly that with his method of working he has never succeeded to obtain a larger yield than 50 percent of the theoretical. In view of this fact the differentiating behavior of the oxy-compounds mentioned according to this invention, was entirely out of the ordinary and could not be expected.

It should be understood that instead of salts of the toluol-sulphon-alkyl-amids it is possible to employ other amido-acid-salts.

The hydroxy- ω amino-aceto-phenones with a substitution-group adjacent the nitrogen-atom are obtained in their turn by the treatment of the compounds mentioned above with reference to the type A by treating the compounds of this type A with mineral acids at an increased temperature, and by this treatment the acyl disposed at the hydroxyl-group is likewise removed. In this manner the N-alkyl-substituted hydroxy- ω -amino-acetophenones can be obtained in a comparatively easy manner and in pure condition and at a highly satisfactory yield. My present process of obtaining omega-substituted hydroxyl-amino-substituted acetophenone-bodies or hydroxy-phenyl alkyl or aryl amino or acyl-amino ketone bodies is clearly distinguished from my own previous suggestion of acting with mono- and with di-alkyl-amines on monohydroxy- ω -amino-acetophenone-derivatives by the fact that a much better yield and better products are obtained than in my previous process in which there is the difficulty that a resinous mass is first separated as a result of the formation of pyrazines produced by the action of the free amines of the hydrocarbons. In my present process this difficulty is overcome by the absence of such free amines and by the use of acid-amides with but one mono-valent substituent combined with the nitrogen, the yield being moreover further improved by the use of parent materials in which the hydrogen of the free hydroxyl-group has been substituted or closed by acyl- or alkyl- or aryl-substituents.

Example I.—13 grams meta-acet-oxy-bromine-acetophenone

are shaken up with 11.2 grams para-toluene-sulphone-methylamin-potassium-salt and with about 50 cc. acetone for some hours, the resulting liquor is sucked off from the potassium-bromide that has separated out, and the filtrate is evaporated down to a small volume. The crystalline mass which separates out from the liquid is washed with water and alcohol, and con-

stitutes the desired intermediate product which melts at a temperature between 120 and 121 degrees.

6 grams of this intermediate product are boiled for one hour with 25 cc. of a 55%-aqueous hydro-iodic acid, the aqueous solution is freed from the para-toluene-sulpho-iodide formed by repeated shaking with ether, and it is then oversaturated with ammonia. This will cause the separation of shining leaflets of the meta-hydroxy-methyl-amino-acetophenone, melting at 135 degrees C. The hydrochloride of this basic substance, if crystallized from dilute alcohol forms crystals of the melting point 234 degrees C. yield being 66%.
 15 *Example II.*—72 grams para-benzoyl-hydroxy-omega-bromo-acetophenone are shaken for one hour with 50 grams para-toluene-sulphone-methyl-amine-potassium-salt and acetone; the resulting separated mass is washed with water and alcohol and the crystalline residue of the acetone-mother-liquor is treated in the same manner. Thus the desired compound is obtained at a yield of 90 percent of the theoretical quantity.—Then this compound is treated with fuming hydrochloric acid at 100 degrees C., and the mixture obtained is then operated upon as in the first example, and by this means upon precipitation of the aqueous solution with ammonia the para-hydroxymethyl-amino-acetophenone is obtained which melts at 148 degrees C. The hydrochloride melts at 238-240° Centigrade. Upon analysis the following composition was found 53.37% C, 6.12% H (calculated for $C_9H_{12}O_2NCl$ = 53.57% C, 6.00% H).
 35 It is to be understood that the scope of the invention is not intended to be limited beyond

the terms of the appended claims or of the requirements of the prior art, and that the invention may find expression in other exemplifications beyond those hereinbefore recited.

I claim:—

1. As a new product meta-hydroxy-methyl-amino-acetophenone having the structural formula

80

melting at 135° C. and forming glossy leaflets.

2. A sulpho-amido substitution product of omega substituted acetoxy-acetophenone having the structural formula

85

90

95

and melting at a temperature of between 120 and 121 degrees C.

3. A method for making mono-hydroxy-N-alkyl-amino-acetophenones which consists in reacting compounds of the type

100

in which X is an halogen and Y an alkyl or acyl group, with alkali-metal salts of aromatic sulfamides, separating the resulting organic compound from the alkali metal halogenide formed and saponifying said organic compound.
